UNITED STATES PATENT OFFICE.

EDWIN G. LYNCH, OF PARISH, NEW YORK.

HOLDBACK FOR VEHICLES.

SPECIFICATION forming part of Letters Patent No. 321,375, dated June 30, 1885.

Application filed April 25, 1885. (No model.)

To all whom it may concern:

Be it known that I, EDWIN G. LYNCH, of the village of Parish, in the county of Oswego and State of New York, a citizen of the United States, have invented certain new and useful Improvements in Holdback Attachments, of which the following is a specification, reference being had to the accompanying drawings, in which—

10 Figure 1 is an elevation. Fig. 2 is a transverse section. Fig. 3 is a detail of ring. Fig. 4 is a transverse section of the holdback without under flange.

15 The object of my invention is to produce a holdback self-hitching, self-adjusting, and self-relieving in its construction and operation.

20 It consists of the several devices and combinations of devices which are hereinafter described, and are specifically set forth in the claims.

25 It is constructed as follows: A is the thill. B is the holdback, consisting of a tubular or slotted body, *a*, having a projecting horn, *b*, as shown in the drawings. Upon the lower inner edge of this body *b*, I construct an outwardly-projecting flange, *c*, in which are screw-holes. C is the tug, which passes lengthwise through the body *a*. D is the holdback-30 strap provided with a ring, *d*, upon its end, usually of rectangular form.

35 The holdback B is secured upon the thill by screws, so that the body lies upon and along the inner face or edge of the thill with the horn *b* in front.

In hitching up, I pass the tug C through the ring *d* and then through the holdback B, and as I draw the tug back it carries the ring back under the horn *b* until the parts assume the relative positions shown in the drawings; 40 and when strain is applied to the strap D the ring *d* draws against the horn *b* and through that against the thill.

When I unhitch the tug from the whiffle-tree, I draw it out through the body *a*, and the 45 tug carries with it the ring *d*, so that when the tug is wholly withdrawn this ring is entirely released from the horn *b*, and when so released the strap D and ring together act as a lazy-strap to support the tug and keep it off from 50 the ground. In this manner the tug acts both to draw the ring into its engagement under the horn and to disengage it.

What I claim as my invention, and desire to secure by Letters Patent, is—

55 1. A holdback attachment consisting of a tubular or slotted body, *a*, provided with a front horn, *b*, constructed substantially as shown and described.

2. The combination of the holdback B, provided with horn *b* and thill A, with the tug C, and strap D, provided with ring *d*, constructed and operating together, substantially as shown and described.

60 In witness whereof I have hereunto set my hand this 20th day of April, 1885.

EDWIN G. LYNCH.
